UNITED STATES PATENT OFFICE.

DAVID STEVENS AND SAMUEL L. THOMAS, OF MINNEOLA, KANSAS.

CONCRETE-MIXER.

No. 921,480.

Specification of Letters Patent.

Patented May 11, 1909.

Application filed August 5, 1908. Serial No. 427,094.

To all whom it may concern:

Be it known that we, DAVID STEVENS and SAMUEL L. THOMAS, citizens of the United States, residing at Minneola, in the county of Clark and State of Kansas, have invented new and useful Improvements in Concrete-Mixers, of which the following is a specification.

This invention relates to concrete mixers, the object of the invention being to provide a simple, compact and practical machine for mixing sand and cement in the manufacture of concrete, the machine being adapted to mix the ingredients in the proper proportions and discharge the same from the machine after the mixing operation has been completed.

With the above general object in view, the nature of which will more fully appear as the description proceeds, the invention consists in the construction, combination and arrangement of parts as herein fully described, illustrated and claimed.

In the accompanying drawings:—Figure 1 is a plan view of a concrete mixing machine embodying the present invention. Fig. 2 is an end view thereof. Fig. 3 is a vertical cross section taken in line with the compartment hopper.

The concrete mixer contemplated in this invention comprises a suitable supporting frame 1 of any preferred construction which forms a support for a semi-cylindrical trough 2 in which the mixing operation takes place. Extending lengthwise within said trough is the main shaft 3 provided with rotating spokes 4 to which are keyed a corresponding number of mixing blades, shovels or beaters 5, the main body portions of which are flat or straight as shown in Fig. 3 while the outer portions thereof are curved forward in the direction of rotation of the shaft as shown in said figure and further the adjacent edges of the blades overlap each other as shown in Fig. 1. The arms 4 in addition to being radially arranged, are arranged in spiral series so that a general spiral arrangement is also imparted to the blades or shovels 5 as clearly indicated in Fig. 1, whereby said shovels in addition to

commingling the sand and cement also operate to constantly advance the mixture thereof toward the discharge orifice 6 in the machine which is formed by leaving the trough 2 open at the discharge end of the machine.

Mounted upon the trough 2 and the supporting frame 1 thereof is a base 7 of a double or compartment hopper 8 comprising a relatively large sand compartment 9 to the relatively smaller cement compartment 10. In the bottom of the sand compartment 10 is a spiral conveyer or auger 11 while in the bottom of the cement compartment there is a relatively smaller spiral conveyer or auger 12. These conveyers 11 and 12 advance the cement toward discharge openings in the end wall of the hopper which lead directly into the trough occupied by the rotating shovels or blades 5. The shafts of the conveyers 11 and 12 are provided on their projecting ends with sprocket wheels 13 and 14 respectively over which runs a driving sprocket chain 15 which is actuated by a larger sprocket wheel 16 on the main shaft 3. In this way, the different shafts are properly timed to mix the ingredients in the proper proportions.

The shaft 3 may be driven either by hand or by any suitable motive power.

The compartments 9 and 10 of the double hopper are divided from each other by an inclined partition 17 flanged at its opposite end as shown at 18 and rabbeted or bolted to the opposite walls of the hopper.

We claim:

A concrete mixer comprising a trough, a hopper compartment arranged to discharge at one end into the trough, spiral conveyers of different diameters rotatably mounted in the bottom of the trough, an inclined partition separating said hopper compartment, a main rotating shaft extending lengthwise within the trough and having spokes secured thereon in zigzag positions, rectangular shaped blades secured to said spokes, the body portions of which are flat and having their straight inner edges contacting wholly with the main shaft in inclined positions so that the blades will be spirally arranged on said shaft, the outer edges of the blades hav-

ing inclined curved portions which extend over the flat body portions so as to be arranged in the direction of the rotation of the shaft and the adjacent edges of the blades overlapping each other, and means for operating the conveyer shafts and the main shaft, substantially as specified,

In testimony whereof we affix our signatures in presence of two witnesses.

DAVID STEVENS.
SAMUEL L. THOMAS.
